COMBINED SEAMING AND PINKING MECHANISM

Max Popper, Brooklyn, N. Y., assignor to Lewis Invisible Stitch Machine Company, St. Louis, Mo., a corporation of Maine

Application December 28, 1942, Serial No. 470,357

1 Claim. (Cl. 112—122)

The invention herein disclosed relates to a pinking mechanism adapted to be mounted on a sewing machine and operated in timed relation with respect to the stitch-forming mechanism. More particularly, the invention relates to a pinking mechanism of the kind known as a "chopper" type in which co-operating, relatively movable V-shaped knives partake of a relative, substantially reciprocatory movement.

An object of the invention is to provide a pinking mechanism of this kind that is substantially complete as a unit. Another object of the invention is to provide a mechanism of this kind in which the co-operating knives are urged into pressure contact as the knives approach cutting relation and in which the pressure is relieved as the knives move away from cutting relation. A further object of the invention is to provide a mechanism of this kind in which substantially all of the operating mechanism is enclosed. Another object of the invention is to provide a mechanism of this kind that is compact, simple in construction, comparatively inexpensive to manufacture and reliable in operation.

The foregoing objects and certain advantages that will hereinafter appear are realized in the embodiment of the invention illustrated in the drawings and described in detail below. The drawings include:

Fig. 1 which is a side elevation of a sewing machine with a pinking attachment thereon;

Fig. 2 which is an enlarged fragmentary elevation, partly in section;

Fig. 3 which is a section taken on the line 3—3 of Fig. 2;

Fig. 4 which is a plan of the pinking mechanism;

Fig. 5 which is a side elevation of the same;

Fig. 6 which is a bottom plan of the same;

Fig. 7 which is a sectional elevation taken on the line 7—7 of Fig. 4; and

Fig. 8 which is a front end elevation of the same.

The sewing machine illustrated in the drawings, is a standard sewing machine, more particularly, it is a machine known in the trade as a "Singer 400." This machine includes a frame which consists of a base 1, a standard 2, extending from the base at one end thereof, and an overhanging arm 3 extending from the upper end of the standard, over and parallel to the base. On the end of the arm 3, there is a head 4 in which the needle bar 5 is reciprocally mounted. The needle bar carries a needle 6. The machine illustrated is a two-thread or lock-

stitch machine having a rotary hook and bobbin below the base (not shown) cooperating with the needle. The usual thread-handling mechanism (not shown) is also provided for effecting a series of stitches as the machine is operated.

In the arm 3, there is journaled a main shaft 7 through which the stitch-forming mechanism of the sewing machine is actuated. The shaft 7 extends through the end of the arm at the standard. On the extended end of the shaft 7, there is mounted a pulley 8. Through this pulley the main shaft of the sewing machine is driven by an electric motor (not shown) in the usual manner.

15 On the base 1 of the sewing machine, there is mounted a pinking mechanism that includes a frame 9 secured as by bolts to the base. The pinking mechanism illustrated is of the kind known as the "chopper" type. It includes a

20 ledger blade 10 substantially parallel to the base and having a V-shaped opening forming cutting edges and a male V-shaped knife 11, positioned and arranged to co-operate with the ledger blade. The male knife is mounted on a male knife carrier 12 that is pivotally secured to one end of

25 a lever 13. The lever 13 is pivotally mounted between its ends in the frame 9 and extends through the end of the frame 9. Oscillation of the lever 13 effects substantially reciprocatory movement of the male knife 11 with respect to the ledger blade 10.

30 For the purpose of effecting pivotal movement of the lever 13, a drive mechanism is provided. This drive mechanism is driven from the main shaft of the sewing machine. To this end, a spur gear 14 is secured on the main shaft 7 of the sewing machine for rotation therewith. A bracket 15 supports the driving mechanism through which the pinking mechanism is actuated.

35 The bracket 15 extends up from the base within the standard 3. It is provided with a flat end section 16 that is secured to one face of a bearing lug 17 formed on and extending from the base 1. The bearing lug 17 is provided on the machine as a bearing for a shaft 18 through which the rotary hook of the stitch-forming mechanism is driven. Counter-sunk machine screws 19 secure the flat end section 16 of the bracket 15 to the bearing lug 17. The opposite end of the bracket 15 includes a pair of axially aligned, spaced bearings 20 and 21. In these bearings a drive shaft 22 is journaled. The drive shaft carries a gear 23 secured thereon for rotation therewith. Extending from the bearing

21 there is an arm 24. On the end of the arm 24, there is formed a bearing 25 in which a shaft 26 is journaled. The shaft 26 is spaced from and parallel to the shafts 7 and 22 and is located substantially between these shafts. On one end of the shaft 26, there is secured a spur gear 27 which meshes with both of the gears 14 and 23. The shaft 26 is held in the bearing by the gear 27 and a collar 28 secured on the opposite end of the shaft. With this arrangement, the gears 14, 27 and 23 constitute a reduction gear train for driving the shaft 22 at a lower speed than the shaft 7. For driving pinking mechanisms of the type illustrated, this reduction may desirably be either two to one or three to one.

22 The shaft 22 extends through the bearing 21 which extends, slightly, through an opening in the wall of the standard 3. On this extended end of the shaft there is secured a collar 29 having a crank pin 30 extending therefrom. The crank pin 30 has a ball formed therein which is received in a complementary socket 31 secured on one end of a connecting rod 32. On the opposite end of the connecting rod 32, there is secured a like socket 33. This latter socket receives a ball formed on a pin 34 secured in and extending from the end of the lever 13.

23 With this arrangement, the drive shaft 22 is driven in a constant ratio and in timed relation with respect to the main shaft 7 of the sewing machine and in consequence with respect to the stitch-forming mechanism. Through the crank 29 and the connecting rod 32, the lever 13 of the pinking mechanism is oscillated. The relation is such that the male knife enters the ledger blade to effect a cut on the downward stroke of the needle, while the material acted on is stationary. The movements of the male knife are, of course, less in number than the reciprocations of the needle.

24 The pinking mechanism is illustrated in detail in Figs. 4 to 7 inclusive. In this pinking mechanism, the actuating lever 13 is housed within the frame 9, extending therefrom at the ends thereof. The lever is mounted to oscillate about a pivot pin 35 extending between the walls of the slot 36 within which the lever is mounted and extending through a bearing lug 37 formed on the lever.

25 The frame has side flanges 38 on opposite sides thereof through which it is bolted to the base of a sewing machine. For this purpose bolt slots 39 are provided through the flange. The frame also has a front extension or flange 40 to which the ledger blade 10 is secured as by machine screws 41. Also secured on the extension 40, by a thumb screw 42, there is a cloth or edge guide 43 which serves to guide the edge of the cloth in passing through the mechanism.

26 The forward end 44 of the frame 9 through which the lever 13 extends is curved in an arc about the axis of the pivot 35. The corresponding end of the lever 13, that portion outside of the frame 9, is of greater thickness than the remainder of the lever and it is bifurcated to form spaced arms 45. The edges, extending on either side of the opening to the slot, of the lever 13 are also curved in an arc about the axis of the pivot 35 and thus they have surfaces complementary to the curved end of the frame 9. These surfaces of the lever 13 ride along the curved surface 44

of the frame 9 when the lever is oscillated. The bifurcation of the end of the lever provides a slot in the top of the lever, the arms 45 extending above the lever proper.

27 Between the arms 45 of the lever 13, the knife carrier 12 is pivotally mounted. This knife carrier is in the form of a bell crank lever and it is mounted for movement about a pivot 46 extending between the arms 45. To one arm 47 of the knife carrier, the male knife 11 is secured by a bolt 48. The other arm 49 of the bell crank lever has a reduced extension 49a extending into the frame 9. To the arm 49, one end of a leaf spring 50 is secured. The leaf spring extends into the frame and it is engaged by an adjustable abutment pin 51 threaded into the top of the frame 9.

28 The spring 50 serves to provide a yieldable force in a direction to move the knife holder about the pivot. The male knife, even when out of the ledger blade is restrained from movement away from registering relation with the ledger blade by guide lugs 52 extending from the ledger blade. Thus the spring serves to effect a pressure engagement of the edges of the male and female knives as the male knife moves into the female knife. This pressure is exerted in a direction substantially parallel to the cutting plane and in a direction towards the apex of the cutting edges. By locating the abutment pin 51 (Fig. 7) in the relation illustrated with respect to the pivot 35, the spring pressure increases as the male knife moves downwardly into cutting relation with the ledger blade and it is relieved when the male knife withdraws to the position illustrated. This is a desirable relation as it substantially reduces the wear on the knives, particularly the cutting edges.

29 From the foregoing description of the combined seaming and pinking mechanism illustrated in the drawings, it will be seen that by this invention there is provided a simplified pinking mechanism in which the actuating parts are substantially enclosed and in which the pressure between the knives varies with the relative movement of the knives.

30 It will be obvious that various changes may be made by those skilled in the art in the details of the embodiment of the invention illustrated in the drawings and described in detail above within the principle and scope of the invention as expressed in the appended claim.

31 I claim:

32 A pinking mechanism for a sewing machine having a base, stitch-forming mechanism and operating means for the stitch-forming mechanism, which pinking mechanism includes in combination a frame adapted to be secured to the base of a sewing machine, a ledger blade mounted on the frame and having a V-shaped opening therein, a lever pivotally mounted on the frame and adapted to be actuated by the operating means for the stitch-forming mechanism, a knife carrier pivotally mounted at one end of the lever, a V-shaped knife, carried by the knife carrier and positioned to cooperate with the ledger blade, stationary guides engaging the V-shaped knife, a leaf spring secured at one end of the knife carrier, and an abutment for the leaf spring spaced away from the knife carrier a distance greater than the pivotal axis of the lever.
